[57] ABSTRACT

This invention relates to inflatable barrier means for retaining water in a watercourse, for example a river, and of the kind comprising at least one inflatable enclosure secured to an element anchored directly or indirectly in such watercourse and constructed in such a fashion as to prevent erosion.

In order to enable the barrier means to be easily removed from the watercourse, for example to be used in another location, the invention provides means for anchoring the enclosure in relation to the watercourse bed, and this means incorporates an anchoring strip of supple material such as rubber that is securable to the bed, and this strip has a free extremity or edge provided with one or more means for removably connecting the barrier to said strip.

The anchoring strip may be secured to a rigid member arranged to be laid down in the soil of the bed of the watercourse and this rigid member may take the form of a block of masonry. Alternatively, the anchoring strip may be embedded in the soil of the bed of the watercourse by digging out a transverse trench using the removed aggregates to form a temporary dam, laying the anchoring strip in the trench preferably at an angle of 45° to the plane of the bed, and then filling up the trench with the aggregates previously dug out, thus to secure the strip in relation to the soil of the bed.

SHEET 1 OF 3

INFLATABLE BARRIERS FOR WATERCOURSES

The present invention relates to inflatable barriers of the kind comprising a flexible enclosure which is applied against the bed of a watercourse such as a river, and is then inflated by filling it with water, either to form a screen and create a water retention means, the overflow of the water discharging over the enclosure, or for causing the course of the water to deviate if the barrier is positioned so as not totally to traverse the watercourse.

The use of inflatable barriers is extremely interesting both because they allow modification with precision of the level of the watercourse or the river in which they are positioned and because their positioning is simple and quick.

Despite the advantages associated with the use of such inflatable barriers, however, they are only rarely used in practice. This stems from the fact that such inflatable barriers have hitherto been anchored to the bed of the watercourse or the river by means which are not very satisfactory, because they are difficult to put in position and then again, their application is limited.

Thus, for example, it is known to anchor the inflatable enclosure to a block of masonry or stonework by several wedges, clamps or similar fixing devices secured by bolts or pins previously sealed into the stone. Fixing devices of this kind do not allow a simple attachment or removal of the enclosure.

Often the inflatable enclosure is made up by folding on itself a thick rubber strip and applying firmly one on the other the two superimposed edges which are imprisoned on the one hand between the masonry block anchored in the river, and, on the other hand, a rigid metal plate, wedge or clamp which is locked against the two superimposed edges of the strip of rubber and against the masonry block by means of screws and bolts or pins sealed into the said block; using the same means, the enclosure is made water-tight as well as being fixed in relation to the watercourse.

Sometimes, the inflatable barrier is a thick rubber tube which has a cushion along one of its generatrices, similar to the beaded edges of a tyre, which is inserted in a rigid profiled member fixed by screws and bolts to the masonry block.

The attachment and removal followed by a reattachment of such inflatable enclosures are complicated operations, if only due to the deformation of the fixing means, arising out of the circumstances to which they are submitted during the time the enclosure has been in service, and to the fact that it is in practice necessary to render the river dry, for example to seal new bolts into the stonework mass or to form and/or to fix the new enclosure in the manner which has been described above.

Moreover, since it is in practice impossible to insert between the masonry block and the metal plate more than two layers to render the enclosure water-tight, it is necessary to effect water-tightness by utilising thick rubber layers so that they shall resist both the abrasion which is brought about by friction on the bed, and the erosion and the various shocks caused by objects in the water on its upper face.

It is, therefore, an object of the invention to remove or minimise these drawbacks, and in addition to offer other advantages in certain embodiments thereof.

These and other objects and advantages will become apparent in what is to follow.

In barriers according to the invention, the inflatable enclosures are in the form of water-tight tubes and having along one generatrix one or more extensions by which the barriers are fixed by removable fixing means to a supple strip itself directly or indirectly fixed to the bed of the watercourse. Barriers according to the invention, are constituted by one or more inflatable enclosures which are removably associated with a supple strip, for example of rubber, itself directly or indirectly fixed to the bed of the river.

This latter strip may be connected to a masonry block anchored in the watercourse which moreover prevents erosion; it is thus indirectly fixed to the watercourse. It may alternatively be embedded in the bed of the watercourse so as to be anchored there and prevent erosion; in this case, it is fixed directly to the watercourse.

The connection of the inflatable enclosure to the strip fixed to the river can be effected by any known means that allow it to be removable; for example, there may be rapid connection means such as a sliding closure, a closing member of the "touch and close" type known under the Registered Trade Mark "VELCRO," or any other connecting means which is readily removable such as a system of hooks and eyelets. The supple strip fixed directly or indirectly to the watercourse and made from a material which is rot-proof and is inert to water, remains in place and thereafter it is simple to remove the enclosure and replace it with a new one, since it is only necessary to operate the means connecting this strip to the extensions with which the enclosure is provided.

This also allows the inflatable part of the barriers to be made more economically and more appropriate for the service which is demanded of them. For example, the enclosure may be constituted by a simple inflatable bladder which is not very thick and not in itself actually resistant to abrasion and erosion which keeps at the desired height a mat which forms a screen and which protects the said bladder from erosion. This bladder may also rest on another mat placed on the masonry block or on the bed of the watercourse, the said mat protecting it from abrasion.

In order that the invention may be more clearly understood, several embodiments thereof will now be described with reference to the accompanying drawings by way of example, and in which;

FIG. 1 is a cross-sectional through a barrier according to the invention fixed to the bed of a watercourse by the intermediary of a masonry block,

FIG. 2 is a cross-section through a second embodiment of barrier positioned on another form of masonry block,

FIG. 3 is a cross-section through a third embodiment of barrier positioned on a masonry block,

FIG. 4 is a cross-section through another embodiment which is fixed by the intermediary of a mat embedded in the bed of the watercourse,

FIG. 5 is a cross-section which shows the barrier of FIG. 4 being installed,

FIG. 6 is a cross-section which shows traction tests on the mat of FIGS. 4 and 5 embedded in aggregates,

FIG. 7 is a cross-section at the front face of a modular barrier means in accordance with the invention, and

FIGS. 8 and 9 show in plan two inclined barriers made in accordance with the invention.

Referring now to the drawings, in order to instal the barrier shown in FIG. 1 there is previously formed at the bottom of a watercourse, a concrete apron or beam 10 to which there are fixed, for example, by rag bolts 11, a supple connecting strip 12 constituted by a layer of rubber or similar material.

The downstream edge of this strip incorporates one part of a removable connecting means to which is fixed the complimentary part of the said connecting means, the said part being secured to or integral with an extension strip 13a which forms part of an inflatable enclosure 13. In this case, the extension 13a which is continuous, extends along the whole of the length of the enclosure and the connecting means is in this embodiment constituted by hooks 14 which are 'S'-shaped and whose ends are introduced into eyelets 15 and 16 provided on the free edges of the extension strips 13a and of the anchoring strip 12. The enclosures may equally well have several extensions regularly disposed along the same generatrix. The removable connecting means 14 may equally well be constituted by sliding closure means of synthetic material preferably insensitive or only slightly sensitive to water and to the micro-organisms which it contains. This means may, however, take other forms, for example, it may be a closure of the "touch and close" type (VELCRO) or, in fact, any other connecting means found convenient.

Thus, the inflatable enclosure 13 of the barrier may be easily and rapidly attached and removed. If the barrier is to be removed, then the anchoring mat 12 is left on the apron or beam 10 and the enclosure 13 may be used again by fixing it to another mat secured to another apron or beam elsewhere in the same watercourse or in another watercourse.

The barrier shown in FIG. 2 is constituted by a masonry block 15, one part of which lies above or overhangs the bed of the watercourse; the inflatable enclosure 16 is fixed to the top of this block 15. A fixing strip 17 for fixing the enclosure 16 to the block 15 comprises a supple mat fixed to the upstream face 15a of the block 15, and is connected to the inflatable enclosure by means of an extension strip 16a by removable connecting means 18 similar to those described above in connection with FIG. 1.

The inflatable barrier shown in FIG. 3 constitutes another embodiment of the invention which is schematically represented. A part thereof 20 constituting a supple assembly which is located in the river to form the barrier, comprises a plurality of elements each one of which is individually connected in a removable manner to an anchoring strip 21 fixed to a masonry block shown at 19. In this embodiment, the anchoring strip 21 has on its upper edge a plurality of strips so as to permit the connection of the elements of the part 20. In this embodiment, the part 20 of the barrier includes an anti-abrasion mat 20a located on the top of the block 19 and fixed by a removable connecting means 22 to a strip 21a which is secured to or integral with the anchoring strip 21. On this mat 20a where rests an enclosure of bladder 20b having an extension 20c which is fixed by a removable connecting means 23 to another strip 21b of the anchoring strip 21. The inflatable bladder 20b supports on its upper face a supple mat 20d fixed by means of a removable connection means to the anchoring strip 21 by the intermediary of another strip

21c fixed to or integral with the anchoring strip. The mat 20d which is not connected to the upper part of the bladder 20b has an excellent resistance to objects which fall over the barrier and thus protects that part 5 of the bladder against which it is applied. It is thus similarly protected as the lower part of this bladder which is protected by the mat 20a against abrasion which is due to permanent friction or rubbing of its lower face against the concrete or aggregates of the block 19.

10 The inflatable enclosure 20b is water-tight but not requiring to have any resistance either to abrasion or shock, it may be relatively thin which makes it very simple to place in position. Its function is to locate and keep in place at the desired height, the mat 20d which the water constantly applies against its upper face. By its inflation and deflation, the bladder 20b raises or lowers the mat 20d on which the abrasion and shocks of the water reservoir are exerted.

15 20 The mats 20a and 20d may each be constituted by a sheet of rubber which is only slightly abradent provided with a reinforcement which, for example, may be of metal, and such mats are simple to make and to place in position.

25 20 The removable connecting means 22, 23 and 24 of the mats 20a and 20d as well as of the bladder 20b may, as described above, be constituted by sliding fastening devices so that attachment and removal of the parts is extremely rapid. They may equally well be made by any other means such as 'S'-shaped hooks whose ends are introduced into eyelets formed along the edges of the two elements to be connected together.

30 35 Instead of previously making a masonry block to which the anchoring strip or mat is positively connected, this anchoring strip or mat may be embedded in the bed of the watercourse so that it may be used as an anchoring means for the barrier and as means for sealing off the soil, to eliminate any risk of erosion. The strip or mat which has a size larger than when it is fixed 40 on a beam or apron may, for example, be made from rubber or any other similar material and may include a reinforcing member which may, for example, be constituted by metal cables.

35 45 The mat offers resistance to tearing-out stresses which varies, for the same length of mat embedded in the ground, in dependance upon the angle formed by the mat to the horizontal. It has been found that these stresses are at a maximum when this angle is in the vicinity of 45°. Surprisingly, these tearing-out stresses to 50 which the mat offers resistance are quite high: about 200 daN per metre of length measured transversely with respect to the river when 0.05 metres is embedded in the bed of the watercourse at an angle with the horizontal in the vicinity of 45°.

55 55 In the embodiment of FIGS. 4 and 5, the supple enclosure 25 is connected upstream to a mat 26 that is embedded in the soil of the watercourse and inclined towards the upstream direction at an angle A of about 45° with the bed of the watercourse. In order to locate 60 the mat 26 of the barrier there is hollowed out into the watercourse bed a transverse trench 27 as is shown in FIG. 5. This trench has a depth appropriate to suit the lower part of the mat to be positioned; the mat 26 is applied against the downstream face of the trench and the aggregate material shown at 28 taken out by the hollowing of the trench, is then put back in place to fill the trench.

This operation of locating the carpet is facilitated by placing the aggregate materials shown at 28 on the upstream side which allows the formation of a dam over part of the height at least and then the mat 26 can be put in position without difficulty in calm water or water which is only slightly disturbed.

At the time of installation of the barrier, it is preferable that the enclosure 25 be connected to the mat 26 and also that the enclosure be completely deflated as is shown in FIG. 5. When the mat 26 is held in place by the aggregate material 28 which has been put back into the trench 27, the enclosure 25 may be placed in position and be inflated in order to put the barrier into commission.

It has been found that the type of anchoring using a supple mat, such as the mat 26, will resist in a surprising manner any traction stresses imposed by the barrier. The excellent resistance to tear-away stresses is no doubt due to the increased friction between the rubber and the aggregate materials and thus to the suppleness of the mat, which, by allowing it to adapt itself to the unevenness, increases the friction.

Tear-away tests carried out in the laboratory with a mat 1 metre square, having a thickness of 4.5mm, have produced the following results (the mat being positioned at an angle of 45° in aggregate materials over which has passed a current of water).

Traction Stresses in daN	50	100	150	200
Length of the mat (in centimetres)	35	55	71	85

In order to carry out these tests, there was fixed at the free end of a mat 29, as shown in FIG. 6, a traction device, including a dynamometer 30 as is schematically shown; then the mat 29 was pulled or torn out along a line of movement represented by the direction of the arrow F.

In all the embodiments referred to above, the part forming the actual barrier may be made up of several elements. For example, the barrier shown in FIG. 7 is formed by a series of elements which may be simply manufactured by mass production methods. It comprises bladders 31 placed end to end in a lateral direction, which bladders rest on mats 32 and support tipping mats 33; the mats and the bladders are in this embodiment fixed to a masonry block 34 constructed over the whole width of the river; the co-adjacent edges of the tipping mats overlap. The bladders are in all cases of small length, for example, of the order of 2 to 3 metres; this avoids the formulation of oscillatory movements and thus stresses one of the causes that often engender the rapid destruction of inflatable barriers in use at this time.

In this embodiment, one mat 32 and one mat 33 are used for each bladder 31, but it will be well understood that one mat 32, or one mat 33 may be used for a plurality of bladders if required.

The possibility of manufacturing the barriers in the form of modular elements ensures that not only a barrier of great length may be made, but that the barrier

may be produced at a relatively low cost. Barriers according to the invention have numerous applications, for example, they may be used as shown in FIGS. 8 and 9 as inclined barriers placed across the watercourse or as directing barriers, that is to say, to form obstacles to redirect the flow of water.

I claim:

1. In inflatable barrier means for retaining water in a watercourse, comprising at least one inflatable enclosure secured to an element anchored directly or indirectly in the watercourse and constructed in such a fashion as to prevent erosion, the improvement which consists in that the means for anchoring the enclosure in relation to the bed of the watercourse incorporates an anchoring strip of supple material securable to said bed and having a free extremity provided with one or more means for removably connecting said enclosure to said anchoring strip.
2. An inflatable barrier according to claim 1 wherein said strip is secured to a rigid member arranged to be laid down in the soil of the bed of the watercourse.
3. An inflatable barrier according to claim 1 wherein said strip is embedded in the soil of the bed of the watercourse.
4. An inflatable barrier according to claim 3 wherein said strip embedded in the soil forms an angle of about 45° with reference to the plane of the bed.
5. An inflatable barrier according to claim 1 wherein a mat is secured to an element anchored in said watercourse and extends over the upper face of said inflatable enclosure without being integral therewith, said inflatable enclosure supporting said mat to form a screen against water, and for protecting said enclosure.
6. An inflatable barrier according to claim 1, wherein a mat is located between a lower face of said inflatable enclosure and said bed of said watercourse.
7. An inflatable barrier according to claim 1, wherein said connecting means for said anchoring strip comprises a sliding fastener.
8. An inflatable barrier according to claim 1, wherein said connecting means comprises hooks of 'S'-shape cooperating with eyelets formed in the co-adjacent edges of the elements to be connected together.
9. An inflatable barrier according to claim 1, which comprises a plurality of inflatable barriers located end to end and at least one mat supported by said enclosures.
10. A method of installing an inflatable watercourse barrier according to claim 3, which method consists in hollowing out a trench transversely of said watercourse, positioning aggregate materials constituted by the material dug out of said trench, upstream of said trench to constitute a dam for holding back water in said watercourse, applying an anchoring mat against the downstream face of a wall of said trench and filling in said trench by utilising the aggregate materials of said dam, thus to secure said anchoring mat in position in said trench, whereupon at least one inflatable enclosure is attached to said anchoring mat by removable connecting means.
